FIG. 2.

UNITED STATES PATENT OFFICE.

CHARLES D. ALLAN, OF CHICAGO, ILLINOIS.

SLIDE-RULE.

1,110,855.

Specification of Letters Patent. Patented Sept. 15, 1914.

Application filed March 19, 1914. Serial No. 825,742.

To all whom it may concern:

Be it known that I, CHARLES D. ALLAN, a citizen of the United States, and a resident of Chicago, in the county of Cook and State of Illinois, have invented a certain new and useful Improvement in Slide-Rules, of which the following is a specification.

My invention relates to engineers' slide-rules, having the general characteristics of construction of the Mannheim rules, and consisting of two fixed bars, joined together by a cross piece, and a movable slide interposed between them, the faces of the bars and slide, on which the various logarithmic scales are arranged being in a common plane, and my invention relates more particularly to an improved and special arrangement of the said logarithmic scales, by means of which equations showing the mathematical relationship between volume of flow, loss of pressure due to friction, and diameter of conduit and between volume of flow, loss of pressure due to friction and velocity of flow, of fluids flowing in conduits of circular cross section may be solved, and also the application of these equations to the determination of the combinations of standard commercial sizes of pipe best suited to the purpose in hand.

In the designing of systems of heating and ventilation, to which my invention is particularly, though by no means exclusively, adapted, I know of no mechanical device by which the solution of equations of the above described character can be solved, and in all engineering offices, of which I have knowledge, where such work is regularly carried on, the mathematical relationships between volume, loss of pressure due to friction, diameter of pipe and velocity of flow, are laboriously tabulated or charted, the data so arranged covering only a limited range, by reason of the labor involved in its computation and arrangement for use.

My invention, therefore, has for its object to provide a rule by means of which problems in this field, such for examples as those involved in the flow of steam and water in standard steel and wrought iron pipe, may be readily and accurately solved over a large range of variation.

My invention has for its further object to determine the loss of pressure due to friction of a constant volume of flow through equal lengths of consecutive sizes of stand-

ard commercial pipe. For example, if in a system of hot water heating, the supply line to a radiator is made of one size of pipe, and the return connection of the next smaller consecutive size, each being of equal length, and the volume of flow in each equal, a frictional effect would be obtained which would be somewhere between the frictional effect which would be obtained if both supply and return were of the same size as the larger pipe, on the one hand, or of the smaller pipe, on the other hand; or the frictional effect would be equal to that obtained, if both supply and return were of the same size, but of a diameter somewhere between that of the large and small pipes.

The form of slide-rule in most common use, generally known as the Mannheim rule, is practically limited to the solution of equations which take the general form

$$\frac{a}{b} = \frac{c}{x} \text{ or } \frac{a}{b} = \frac{c}{x^2}$$

in which a , b and c are the known quantities and x the unknown quantity, which it is desired to find. This form of equation, however, is not suitable for determining the relative values of the different factors involved in the flow of fluids in circular conduits, as will be hereinafter explained.

In any conduit of circular cross section the volume of flow per unit of time, may be represented by the equation of general form,

$$(1) \quad W = v d^2 C_1$$

in which

W =volume of flow in units of bulk measurement per unit of time.

v =velocity of flow in units of lineal measurement per unit of time.

d =diameter in units of lineal measurement.

C_1 =a constant.

The height of a column of liquid necessary to balance the loss of pressure due to friction in a pipe of unit length may be represented by the equation of general form

$$(2) \quad h = C_2 \frac{v^2}{d^4}$$

in which

h =the height, in units of lineal measurement, of a column of liquid that will balance the loss of pressure due to friction in a conduit of unit length.

v =velocity of flow in units of lineal measurement per unit of time.

d =diameter in units of lineal measurement.

5 C_2 =a constant.

v and d may be successively eliminated from equations (1) and (2) giving two equations, one between volume, friction head and diameter, and one between volume, friction head and velocity that will take the general form

$$(3) \quad \frac{h}{C_3} = \frac{W^x}{d^{2x+y}}$$

15 as between volume, friction head and diameter, and

$$(4) \quad \frac{1}{C_4} = \frac{W^y}{v^{2x+y}}$$

20 as between volume, friction head and velocity, in which C_3 and C_4 are constants and W , h , d and v and the exponents "x" and "y," have the same value as in equations (1) and (2). In the older, and until recently, the most commonly accepted form of hydraulic formulæ, the value given for "x" and "y" are $x=2$ and $y=1$, which values, if applied to equation (2), would show that the friction head loss varies directly as the square of the velocity and inversely as the diameter, and if applied to equation (3) would show that the friction head loss would vary directly as the square of the volume and inversely as the fifth power of the diameter, a discrepancy in its relation to the diameter, that is only apparent and not actual, as W is a composite quantity having d^2 as a direct factor as per equation (1) so that W^2 has d^4 as a direct factor, bringing the relationship of h to d back to direct inverse ratio. Recent and reliable data, deducted from the blocking out of the results of actual experimental work on logarithmic

45 paper, in which the slope of the lines of diameter and velocity determine the values of "x" and "y," or the still more precise method of least squares, show that the actual values of "x" and "y" are fractional, and that "x" is somewhat less than 2 and "y" somewhat more than 1, "2x+y" being, however, still equal to 5, or very nearly so. Consequently, if the values 2 and 1 were assumed, the resulting equations would be only approximately accurate, and the coefficient would hold good over only a limited range of pipe sizes, while if the true fractional values are taken, the equation will hold true for all sizes of pipe, for fluid of the same viscosity and pipe, the inside surface of which is of the same roughness.

60 Referring again to equations (3) and (4) it is evident that they could be partly solved on the regular Mannheim rule, as the constants being known, the relative values of

h , W^x , and d^{2x+y} in equation (3) and $\frac{1}{h^2}$ W^y and v^{2x+y} in equation (4) could be determined, but their complete solution necessitates certain auxiliary logarithmic scales by means of which "x" and "y" roots of W^x and W^y and "2x+y" roots of d^{2x+y} and v^{2x+y} and the reciprocal of h^2 may be directly read, and it is the arrangement of the various logarithmic scales, to facilitate the solution of these equations, and their use in connection with the standard sizes of steel and iron pipe that constitutes the object of my invention, but, in order to illustrate its use by a drawing, it has been necessary to give the exponents "x" and "y" and the constants C_3 and C_4 definite numerical values, and to assume a definite system of units of measurement, as it would obviously be impossible to construct an illustrative drawing of a device of this character, without a system of scale measurement. With this object in view, I have given these exponents and constants a numerical value that has worked out successfully in practice, in designing systems of hot water heating, omitting, however, the detailed algebraic and arithmetical work in deriving them, as not being essential to the principle involved, and giving only the finished equations. Corresponding in form to equations (3) as between volume, loss of pressure due to friction, and diameter, the actual equation used is—

$$(5) \quad \frac{h}{C_5} = \frac{W^{1.876}}{d^5}$$

in which

W =British thermal units per hour given off by the water of circulation. It is a multiple of volume of flow in accordance with the number of heat units which one unit of volume loses in making the circuit.

d =inside diameter of pipe in inches.

h =height in lineal feet of a column of water that will balance the pressure lost in friction through 100 lineal feet of pipe.

55 C_5 =a variable whose value changes in accordance with the drop in temperature of the circulating water in passing through the system. For example, if the circulating water drops 30 deg. in making the circuit, it will give off twice as much heat per unit of volume, as measured in B. T. U. per hour, as if it only dropped 15 deg. Some of the values of C_5 for different temperature drops are as follows:—

For 20 deg. drop $C_5=.000000005328$

" 25 " " " =.000000003506

" 30 " " " =.000000002491

" 35 " " " =.000000001866

" 40 " " " =.000000001452 130

Corresponding in form to equation (4), as between volume, loss of pressure due to friction and velocity, the actual equation is—

$$(6) \quad \frac{1}{C_6} \frac{h^2}{v^5} = \frac{W^{1.25}}{v^6}$$

in which

W=British thermal units per hour carried by the water of circulation. It is a multiple of volume of flow as in equation (5).

v=velocity of flow in lineal feet per second.

h=height in lineal feet of a column of water that will balance the pressure lost in friction through 100 lineal feet of pipe.

C_6 =a variable with different values corresponding to different drops in temperature of the water of circulation, as in equation (5). Some of the values of C_6 for different temperature drops are as follows:—
For 20 deg. drop $C_6 = .000004724$
" 25 " " " = .000003575
" 30 " " " = .000002846
" 35 " " " = .000002347
" 40 " " " = .000001987

C_3 and C_4 are designated as constants in the fundamental equations (3) and (4) while C_5 and C_6 are called variables in equations (5) and (6). This is strictly true in each case, for in the fundamental equations (3) and (4) W represents volume only, to some standard of bulk measurement, while as applied to equations (5) and (6) W represents heat carrying capacity, a multiple of volume, the ratio of which to volume, depends on the heat distributed per some unit of volume, so that if C_5 and C_6 were worked out in detail, it would be found that each was a composite quantity, partly constant, but each a function of a common variable T, which in this case is the drop in temperature of the circulating water, and in steam work might be the product of the density by the B. T. U. per pound weight. Hence in the two equations (5) and (6) five true variables only appear, the friction head loss (h) the B. T. U. per hour (W) the diameter (d) the velocity (v) and the temperature drop (T), of which h, W and T are common to both equations (5) and (6) while d and v each appear in only one of these equations, but have a common exponent.

In the accompanying drawing Figure 1 represents an upper face view of my improved slide-rule. Fig. 2 shows a transverse view taken on line m—m.

L represents the main piece of my improved slide-rule which consists of two fixed parallel bars M and N and a cross piece P

connecting their under faces. The bars M and N are provided at their inner edges with longitudinal grooves h in which is guided a slide Q provided at its edges with longitudinal tongues n which engage the grooves h all substantially in accordance with the well known construction of the Mannheim rules. On the face of the fixed bar M and progressing from left to right in the longitudinal direction of the rule are two logarithmic scales A—B and C. By a logarithmic scale I mean one in which the distance of any number on the scale, from the beginning of the prime division in which it is located, as indicated by its line of graduation, represents the mantissa of its logarithm, a prime division including all numbers between any two consecutive even powers of ten. Scale C adjoining the movable slide Q, which may be considered the key scale of the rule, has four prime divisions, each one-quarter of the graduated length of the rule. Scale A—B has four complete prime divisions and part of a fifth, and is divided into two parts A and B, the part A being placed over and parallel to the part B, so that the range of calculations desired may be covered in a rule of a length that is commercially feasible. The distance on scale A—B representing the mantissa of the logarithm of any number is 1.875 times as great as the distance on the key scale C representing the mantissa of the logarithm of the same number, and the relative longitudinal position of the two scales is such that the zero power of ten, which is unity on each scale, would correspond, if continued to that extent, so that all numbers on scale A—B are situated opposite their 1.875 powers on scale C, and conversely, all numbers on scale C are opposite their 1.875 roots on scale A—B, but all numbers on scale C must be considered as multiples of different powers of ten relative to part A than to part B. The letters T and M following the numbers on scale A—B indicate thousands and millions respectively. On the face of the fixed bar N are also two logarithmic scales H and J—K. Scale H adjoining the movable slide Q and progressing from right to left, opposite to the direction of progression of the key scale C, has two prime divisions, each one-half of the graduated length of the rule, so that all numbers on scale H will be opposite the reciprocals of their squares on scale C and, conversely all numbers on scale C will be opposite the reciprocals of their square roots on scale H. Scale J—K, progressing from left to right, has four prime divisions and part of a fifth, and is divided into two parts J and K as scale A—B is divided, and for the same reason. On scale J—K the distance representing the mantissa of the logarithm of any number is 1.25 times as great

as on the key scale C, so that, the position of unity corresponding on each, numbers on scale J—K are opposite their 1.25 powers on scale C and conversely numbers on scale C are opposite their 1.25 roots on scale J—K. The letters T and M following the numbers on scale J—K indicate thousands and millions, respectively.

On the face of the movable slide Q, are three logarithmic scales D, G and E—F, all progressing from left to right in the longitudinal direction of the rule. Scales D and G are partial reproductions of the key scale C, only the lines of graduation terminating a prime division, or even powers of ten, being indicated. On scale D, in its second prime division from the left end of the rule, are additional lines of graduation, representing different values of the variable C_5 in equation (5) corresponding to different temperature drops of the water of circulation, their distance from the line of graduation at the beginning of the prime division being such as the mantissas of their logarithms call for. In like manner, on scale G are located the various values corresponding to temperature drop of C_6 in equation (6). Scale E—F in the center of the movable slide Q is divided into two parts E and F in the same manner as scales A—B and J—K, and for the same reason, and has one prime division (1 to 10) and parts of two others adjoining. Distances corresponding to the mantissa of the logarithm of any number are five times as great as on the key scale C, or its partial reproductions D and G and the relative longitudinal positions are such that the points of unity would correspond. It is a scale of 5th roots relative to scales D and G.

In addition to the regular lines of graduation in scale E—F heavier lines of graduation indicate in their proper places on the scale the various commercial sizes of steel and iron pipe, from $\frac{1}{2}''$ to 26" O. D., inclusive, located as called for by the mantissa of the logarithms of their inside diameters in inches. Sizes 14" to 26" have, after the figures indicating their size, the letter O. D. indicating "outside diameter" by which commercial pipe over 12" inside diameter is designated. Also between each two consecutive commercial sizes $\frac{1}{2}''$ to 3" inclusive there is shown by a heavy line of graduation an intermediate imaginary size marked I.

Referring to equation (5) it is shown that if the volume (W) of flow remain constant, the loss of head due to friction (h) varies inversely as the 5th power of the diameter (d). I is an imaginary additional size of pipe, of diameter the reciprocal of whose fifth power, is a mean between the reciprocals of the fifth powers of the diameter of the two adjacent commercial sizes between which it is situated, and if such a size ex-

isted it would give the same frictional effect for a given length as though half its length were of the commercial size next below it and the other half of its length of the commercial size next above it, for the same volume of flow.

The method of using my improved slide-rule is as follows:—For the solution of equations between volume of flow, loss of pressure due to friction and diameter, having the form of equation (5), scales A—B, C, D and E—F are used. Whatever the position of the slide, the loss of pressure due to friction, in terms of feet head per 100 lineal feet of main, on scale C, will be opposite the 70 graduations, corresponding to the drop in temperature of the water of circulation on scale D, and the B. T. U. (British thermal units) per hour on part A or B of scale A—B will be opposite the theoretical diameter in inches on part E or F of scale E—F 75 by opposite I mean lying in the same vertical line, perpendicular to the horizontal axis of the rule. By means of the heavy extra lines of graduation on scale E—F 80 representing the commercial sizes of pipe, selection of the size that will most nearly meet any given requirements may easily be made, and each additional line of graduation marked I, between each two consecutive 85 commercial sizes from $\frac{1}{2}''$ to 3" inclusive, indicate an additional imaginary size, which would have the same friction head loss for equal volume of flow, as a line made up of 90 equal lengths of the two consecutive sizes 100 between which it is located. These lines of graduation, of intermediate frictional effect, are not carried above 3" as their use in practical designing is mostly confined to making connections to an individual radiator, where 105 the supply pipe is of one size and the return pipe of another and both of equal length, particularly in gravity hot water heating, where the calculations are carried to a fine point of exactness. For the solution of 110 equations between volume of flow, loss of pressure due to friction and velocity of flow, having the form of equation (6) scales J—K, H, G and E—F are used. Whatever the position of the slide, the loss of pressure 115 due to friction, in terms of feet head per 100 lineal feet of main on scale H, will be opposite the constant corresponding to the drop in temperature of the water of circulation on scale G, and the B. T. U. per hour on 120 part J or P of scale J—K will be opposite the velocity of flow in feet per second on part E or F of scale E—F.

A noticeable feature of my invention is that in the solution of equations of the form 125 of equation (5) as between volume of flow, friction head loss and diameter, and of the form of equation (6) as between volume of flow friction head loss, and velocity of flow, the same scale of 5th roots E—F serves 130

upon which to read diameter in the former instance, and velocities in the latter. This is so for the reason that, in their fundamental forms as per equations (3) and (4), the exponent of diameter (d), and velocity (v) are the same, being equal to $2x+y$.

A few actual examples will serve to still further illustrate the practical operation of my invention.

10 Example:—What would be the diameter and velocity of a flow in a pipe carrying 10,000,000, B. T. U. per hour, on a basis of a temperature drop of 25 degrees, that is each pound weight of water flowing delivers 25 15 B. T. U per hour, the loss of head due to friction being 3 feet per 100 feet?

Place 25 on scale D opposite 3 on scale C and opposite 10 M on part A of scale A—B read 6.9 inches diameter on part E of scale 20 E—F. The nearest commercial size is 7".

Place 25 on scale G opposite 3 on scale H and opposite 10 M on part K of scale K—J read 7.1 feet per second velocity on part E of scale E—F.

25 Example:—The carrying capacity of a main is 20 million B. T. U. per hour and in giving up this volume of heat it drops 20 degrees in temperature and its friction head loss is 2.5 feet per 100 feet, what is its diameter and velocity of flow?

Place 20 on scale D opposite 2.5 on scale C and opposite 20. on part A of scale A—B read 10" (approximate) diameter on part E of scale E—F—10" would be the nearest 35 commercial size.

Place 20 on scale G opposite 2.5 on scale H and opposite 20 M on part K of scale J—K find 8.3 feet per second velocity on part E of scale E—F.

40 Example:—What is the heat carrying capacity and velocity of flow of 2" commercial pipe on the basis of a temperature drop of 35 degrees and a friction head loss of .45 of a foot per 100 feet?

45 Place 35 on scale D opposite .45 on scale C and opposite size 2" on part F of scale E—F read 200,000 B. T. U. per hour on part B of scale A—B.

50 Place 35 on scale G opposite .45 on scale H and opposite 200 T on part J of scale J—K read 7.2 feet per second velocity on part E of scale E—F.

55 Example:—In a system of hot water heating, a radiator gives off 10,000 B. T. U. per hour, what size connections should be made to it that the frictional loss may be at the rate of one-tenth of a foot per 100 lineal feet of main and the drop in temperature 35 degrees?

60 Place 35 on scale D opposite .1 on scale C and opposite 10 T on part B of scale A—B read 1 on part F of E—F lying between the consecutive commercial sizes $\frac{3}{4}$ " and 1". Consequently if one connection to the radiator should be 1" and the other $\frac{3}{4}$ ", and each

be of equal length, the desired frictional effect will be obtained.

Example:—In a system of hot water heating a pipe coil gives off 45,000 B. T. U. per hour, the drop in temperature of the water 70 in passing through the coil is 20 degrees, what size connections should be made to give a frictional loss at the rate of four-tenths of a foot per 100 feet lineal feet of main?

Place 20 on scale D opposite .4 on scale C 75 and opposite 45 T on part B of scale A—B read 1 on part F of scale E—F located between the consecutive commercial sizes $1\frac{1}{4}$ " and $1\frac{1}{2}$ ". Consequently if one connection to the coil is $1\frac{1}{4}$ " and the other $1\frac{1}{2}$ " and both 80 are of equal length, the desired frictional effect will be obtained.

While my invention is useful in heating work, particularly in problems relating to the flow of low pressure steam and hot water 85 in pipes, it is not confined to that art, but is generally applicable to the flow of fluids in conduits of circular cross section, such for example as high pressure steam power piping, air in blow pipe systems for the removal of refuse, or water in municipal or other water supply systems, provided the constants are changed to suit the system of measurements adapted for time and volume, and the exponents made to conform with 90 the viscosity of the fluid, and roughness of 95 interior pipe surface.

I claim:

1. A slide-rule consisting of two fixed bars and a movable slide interposed between 100 them, having two independently coacting series of scales, relating to the flow of fluids in conduits, arranged for the solution of two forms of equations in which five different variables appear, three of which variables 105 appear in both forms of equation, and each of the other two variables appear in only one of the forms of equation, but have a common exponent, each of the two fixed bars of the rule having two logarithmic 110 scales graduated to read the values of two of the variables appearing in both forms of equation, and on the slide two scales each graduated to read the values of the third remaining variable common to both forms of 115 equation, and on the slide a third scale, graduated to read the values of one of the two variables with common exponent not appearing in both forms of equation, when coacting with the two logarithmic scales on one 120 fixed bar and one of the other scales on the slide, the same graduations on said third scale of the slide serving to read the values of the other of the two variables with common exponent, when coacting with the two logarithmic scales on the other fixed bar and the remaining other scale on the slide, the graduations on the said third scale on the slide in each case representing a different 125 character of quantity measured by a differ- 30

6
ent system of units, substantially as described.

2. A slide-rule consisting of relative movable members having coacting scales one of
5 which comprises lines of graduation indicating consecutive sizes of commercial material and additional lines of graduation indicating sizes of material which would produce a mechanical effect which is a mean
10 between the same mechanical effect produced by the two consecutive commercial sizes be-

tween which they are located, substantially as described.

In testimony that I claim the foregoing as my invention, I affix my signature in the 15 presence of two subscribing witnesses this 17th day of March, 1914.

CHARLES D. ALLAN.
